US00D866076S

(12) **United States Design Patent** (10) **Patent No.:** **US D866,076 S**
(45) **Date of Patent:** **** Nov. 5, 2019**

(54) **DENTAL DEVICE**

(71) Applicant: **Personal Care Products, LLC**, Troy, MI (US)

(72) Inventors: **James Steven Pelioles**, Ada, MI (US); **Brett Craib**, Beverly Hills, MI (US)

(73) Assignee: **Personal Care Products, LLC**, Troy, MI (US)

(**) Term: **15 Years**

(21) Appl. No.: **29/691,691**

(22) Filed: **May 17, 2019**

Related U.S. Application Data

(62) Division of application No. 29/605,558, filed on May 26, 2017, now Pat. No. Des. 857,995.

(57) **CLAIM**

The ornamental design for a dental device, as shown and described.

DESCRIPTION

FIG. 1 is a front perspective view of a dental device showing the new design in a first embodiment;
FIG. 2 is a right side view thereof;
FIG. 3 is a left side view thereof;
FIG. 4 is a rear view thereof;
FIG. 5 is a front view thereof;
FIG. 6 is a top view thereof;
FIG. 7 is a bottom view thereof;
FIG. 8 is a front perspective view of the dental device showing the new design in a second embodiment;
FIG. 9 is a left side view thereof;
FIG. 10 is a right side view thereof;
FIG. 11 is a rear view thereof;
FIG. 12 is a front view thereof;
FIG. 13 is a top view thereof; and,
FIG. 14 is a bottom view thereof.
The broken lines in the drawings depict portions of the dental device that form no part of the claimed design.

1 Claim, 10 Drawing Sheets
